Mary W. Phillips, ^{INVENTOR,}
Frank A. Neumann, ^{BY} ATTORNEY.

UNITED STATES PATENT OFFICE.

MARY W. PHILLIPS, OF ATLANTA, GEORGIA.

DESIGN FOR A DOLL.

• 54,449.

Specification for Design.

Patented Feb. 10, 1920.

Application filed July 23, 1919. Serial No. 312,842. Term of patent 7 years.

To all whom it may concern:

Be it known that I, MARY W. PHILLIPS, a citizen of the United States, residing at Atlanta, in the county of Fulton and State of Georgia, have invented a new, original, and ornamental Design for Dolls, of which the following is a specification, reference being had to the accompanying drawing, forming part thereof.

The figure is a plan view of the doll, showing my new design.

I claim—

The ornamental design for a doll as shown.

MARY W. PHILLIPS.
